Primary Examiner — Joseph Kukella*Assistant Examiner* — Darryl J Dardenne(74) *Attorney, Agent, or Firm* — Stoel Rives LLP(57) **CLAIM**

We claim the ornamental design for a bottle, as shown and described.

DESCRIPTION

FIG. 1 is a front perspective view of a bottle with a bottle cap in place according to a first embodiment;

FIG. 2 is a top view thereof;

FIG. 3 is a bottom view thereof;

FIG. 4 is a front plan view thereof;

FIG. 5 is a front perspective view of the bottle with the bottle cap removed;

FIG. 6 is a top view thereof; and

FIG. 7 is a front plan view thereof.

FIG. 8 is a front perspective view of a bottle with a bottle cap in place according to a second embodiment;

FIG. 9 is a top view thereof;

FIG. 10 is a bottom view thereof;

FIG. 11 is a front plan view thereof;

FIG. 12 is a front perspective view of the bottle with the bottle cap removed;

FIG. 13 is a top view thereof; and,

FIG. 14 is a front plan view thereof.

The grayscale gradient of the bottle and bottle cap illustrated in FIGS. 1-14 forms part of the claimed design.
